UNITED STATES PATENT OFFICE.

RICHARD J. ROGERS, OF CHELSEA, MASSACHUSETTS, ASSIGNOR TO THE ROGERS LIQUID METER COMPANY, OF PORTLAND, MAINE.

OSCILLATING WATER-METER.

SPECIFICATION forming part of Letters Patent No. 481,622, dated July 8, 1890.

Application filed January 20, 1890. Serial No. 337,451. (No model.)

To all whom it may concern:

Be it known that I, RICHARD J. ROGERS, of Chelsea, in the county of Suffolk and State of Massachusetts, have invented certain new and useful Improvements in Water-Meters, of which the following, taken in connection with the accompanying drawings, is a specification.

My invention relates to water-meters, and is an improvement upon the invention described in the Letters Patent No. 373,608, granted to me November 22, 1887; and it consists in certain novel features of construction, arrangement, and combination of parts, which will be readily understood by reference to the description of the drawings, and to the claims hereinafter given, and in which my invention is clearly pointed out.

Figure 1 of the drawings is a vertical longitudinal sectional elevation, the cutting plane being on the crooked line 1 1 in Figs. 2 and 3. Fig. 2 is a vertical transverse section through the outer casing and feed-pipe on line 2 2 in Fig. 1, and showing the moving parts in end elevation. Fig. 3 is a horizontal section on line 3 3 in Fig. 2. Fig. 4 is a horizontal section through the feed-pipe and a small part of one side of the inclosing-casing on line 4 4 in Fig. 2; and Fig. 5 is a partial vertical longitudinal section of the oscillating cylinder on line 5 5 in Fig. 2.

In the drawings, A is the measuring-cylinder, provided at the center of its length with the trunnions A' and A'', the former fitting into a bearing in the central ring or belt B, while the latter is provided with a socket to receive the inner end of the discharge-pipe C, which screws into a threaded bearing in the opposite side of said ring or belt B, as shown in Figs. 2 and 3.

The ring B has screwed into each side thereof a hollow cylinder B', having its outer end closed by a head formed therewith or secured thereto, as may be preferred, which, with said ring, constitutes the outer or fixed casing of the meter, within which are inclosed all the working parts of the meter, except the register, and into which all the water flows before passing into the measuring-cylinder A.

The ring B has cast therewith the inlet-pipe B'', on the inner end of which is formed

a valve-seat a, against which is fitted the double-ported slide-valve b, secured to the valve-rod b', extending the whole length of the cylinder A, and having bearings in ears 55 c c, projecting from the heads A' A'' of said cylinder, as shown in Figs. 1 and 2.

The ring B has secured to its inner surface, directly opposite the pipe B'', at a distance therefrom equal to the thickness of the valve b, the valve-seat d, having formed in opposite ends thereof two chambers d' and d'', separated by the partition d', and with the two ports e and e' for the admission of water to one or the other of said chambers according as the valve b is at one extreme or the other of its movement. The chambers d' and d'' have screwed therein the pipes e' and e'', respectively, the outer ends of which are closed by suitable caps, and are provided in 70 their upper sides with the discharge-orifices e' and e'', as shown in Figs. 1 and 2.

Each of the heads A' A'' of the cylinder A has cast in one piece therewith the bent pipe a', and has formed in its inner surface the recess a'' to receive the lever a'', mounted on the horizontal shaft a', extending through one side of the inclosure of said recess, and carrying on its end outside of said head the lever a'', as shown in Figs. 1, 2, and 5. 80

Each of the heads A' A'' has formed on its outer surface the lug or shoulder a'', with which the shoulder f' on the lever f engages to lock the cylinder at the end which is in its most elevated position. The levers f are 85 mounted on studs or fulcrum-pins set in the pipes e' and e'' near the outer end as shown in Figs. 2 and 4, and have set therein or formed thereon near their upper end the laterally-projecting pins or lugs f'', with which 90 the levers a'' engage to move the levers f about their fulcrum-pins and disengage the shoulder f' of said levers from the lugs a'' on the cylinder-heads when the piston D comes in contact with one or the other of the 95 levers a'' and moves it into the recess a''. The upper ends of the levers f are moved toward the heads of the cylinder and into engagement with the lugs a'' by means of a counter-weight f''' (shown in Fig. 5,) and this movement of said lever f, acting through the pins or lugs f'', the levers a'', and rocker-shaft a', 100

causes the levers a^3 to be moved inward toward the center of the cylinder as soon as the pressure of the piston is removed therefrom, as shown in Fig. 5. The lower end of the lever a^5 also engages with the arm g , secured on the end of the valve-rod b' , when it is moved outward by the piston and moves said rod a sufficient distance to reverse the position of the valve b and change the direction 10 of current of water entering the outer casing.

The arms g are extended beyond the valve-rod b' , and have formed on their extremities the pads g' , located above the pipes e^2 and e^3 , and in such positions relative to the orifices 15 e^4 and e^5 that when the valve-rod b' is at the extreme of its movement toward the right of Fig. 1 the pad g' at the opposite or left-hand end of said rod will be directly over the orifice e^4 , and when said rod is moved to the 20 limit of its stroke toward the left of Fig. 2, the pad g' at the right-hand end of said Fig. 2 will be over the orifice e^5 .

E and E' are the inlet-valve casings, and F and F' the exhaust-valve casing, all arranged 25 in a row and connected together and to the curved pipes a' and the trunnion A^2 of the cylinder A by the pipes h , h' , j , j' , k , and k' , as shown in Fig. 1.

The inlet-valve casings E and E' are open 30 at top and bottom, and have fitted therein the valves l and l' , respectively, the stems of which project below the lower ends of their casings, the valve-seats being at the upper end of said casings, as shown.

35 The exhaust-valve casings F and F' have double walls m and m' , the former extending a short distance above the latter, and has its upper end closed by the screw-cap m^2 , as shown. The inner cylinder m' is open at top 40 and bottom, and has formed on its upper end a seat upon which the valve n or n' rests, the stems of said valves projecting below their casings, as shown in Fig. 1.

The inlet-valve casing E and the exhaust-45 valve casing F are connected at their lower ends by the tie-bar o , and the inlet-valve casing E' and the exhaust-valve casing F' are in like manner connected by the tie-bar o' , said bars o and o' each having formed thereon 50 downwardly-projecting ears, to which are pivoted the levers o^2 and o^3 , respectively. The levers o^2 and o^3 extend inward from their pivoted connections to the bars o and o' beneath the exhaust-valve n and n' , respectively, and outward to some distance beyond the inlet-valves l and l' , respectively, and have their outer ends fitted to bearings in blocks p and p' , formed upon or secured to the pipes e^2 and e^3 , as shown in Fig. 1. Said pipes e^2 and 55 e^3 also have formed thereon or secured thereto the blocks or lugs p^2 and p^3 , respectively, with which the inner ends of the levers o^2 and o^3 come in contact when the end of the cylinder to which said lever is connected is depressed, 60 as shown in Fig. 1.

The operation of my invention is as follows: The meter being properly connected in the

line of service-pipe and the outer casing and the cylinder A being filled with water, with the several parts in the positions shown in 70 the drawings, if the faucet be opened to draw water, water from the main enters the outer casing through pipe B^2 , port e , pipe e^2 , and orifice e^4 , and water from the interior of said casing enters beneath the inlet-valve l' , through 75 pipes h' and a' to the interior of the cylinder A at its right-hand end and moves the piston D toward the left of Figs. 1 and 3, and the water in said cylinder at the left of said piston is forced through pipes a' and h at the 80 left of Fig. 1 around the inlet-valve stem l , through pipe j , over the top of the inner cylinder m' of the exhaust-valve casing F , through pipe k and the discharge-pipe C , to and through the faucet. (Not shown.) The 85 piston D , when it has nearly completed its stroke toward the left of Figs. 1 and 3, comes in contact with the lower end of the lever a^3 , (see Fig. 5,) and forces it into the recess a^2 , thereby moving the lower end of the lever a^5 , 90 which, acting upon the arm g , moves the valve-rod b' , with the valve b , toward the left of Fig. 1, and at the same time disengages the lever f from the lug a^6 at the left end of Fig. 1, thus leaving the cylinder unlocked, so that the 95 weight of the piston will cause the left-hand end of said cylinder to be depressed and the right-hand end to be elevated, in which position it is locked by the lever f at that end of cylinder. When the valve b and its rod b' 100 are moved toward the left, as just described, the port e is closed and the port e' is opened, so that the water entering the outer casing passes from the pipe B^2 through port e' , pipe e^3 , and orifice e^5 , and as the pad g' at the right 105 of Fig. 1 has been moved over the orifice e^5 the current or jet of water escaping through said orifice impinges upon said pad and assists in tilting the cylinder, thus enabling me to use a lighter piston than otherwise would 110 be practical.

It will be seen that with the parts in the position shown in the drawings the left-hand inlet-valve and the right-hand exhaust-valve are closed, while the other valves are open, 115 said valves all being moved and held in their open or closed positions by the action of the levers o^2 and o^3 thereon as they are vibrated about their bearings at their outer ends by the rising and falling of the two ends of the 120 cylinder A . I have shown no register, but it is obvious that a register may be applied thereto and worked from the oscillating movement of the cylinder.

What I claim as new, and desire to secure 125 by Letters Patent of the United States, is—

1. In an oscillating water-meter, the combination of the measuring-cylinder A , provided with the trunnions A' and A^2 , an inclosing-casing composed of the central ring or band 130 B , provided with the inlet-pipe B^2 , and the two cylinders B' , screwed into said ring and having their outer ends closed by heads formed in one piece therewith, and the cylinder-sup-

porting discharge-pipe C, screwed into said ring and forming a bearing for the hollow trunnion A².

2. The combination of the outer casing B B', provided with the inlet-pipe B², the branch pipes e² and e³, having orifices e⁴ and e⁵, respectively, the valve-seat d, provided with the two ports e and e', the measuring-cylinder A, mounted in trunnion-bearings at the center of its length, the valve-rod b', extending the whole length of said cylinder and mounted in bearings, so as to be movable endwise therein, the valve b, attached to the middle of said rod and constructed and arranged to operate in conjunction with the seat d and ports e and e' to determine the flow of the inlet-water through the pipes e² and e³, and a pad g', mounted upon each end of the rod b', constructed and arranged to be alternately acted upon by the jet of water escaping from the orifice e⁴ or e⁵.

3. The combination of an oscillating measuring-cylinder provided on the exterior of each head with a projecting lug or shoulder, two latch-levers constructed and arranged to engage with said lugs or shoulders alternately at the end of the cylinder that is the most elevated to lock said cylinder, a reciprocating piston within said cylinder, a pendent vibratory lever mounted in the inner face of each cylinder-head on a rocker-shaft, another pendent lever mounted on each of said rocker-shafts and arranged to act upon the latch-levers to disengage them from the lugs on said heads when the piston comes in contact with and vibrates the levers within the cylinder, substantially as described.

4. The combination of the cylinder A, the piston D, the lugs or shoulders a⁶ a⁶, the levers

f, provided with shoulders f' and the pins or lugs f², the valve-rod b', mounted in bearings on said cylinder and carrying the valve b, the arms g and pads g', mounted on each end of the valve-rod b', the pendent levers a³ and a⁵, and the rocker-shaft a⁴, all constructed, arranged, and operating substantially as described.

5. The combination, in a water-meter, of an oscillating measuring-cylinder mounted on trunnions in an outer inclosing and water-containing casing, an inlet-pipe opening into said outer casing, a discharge-pipe opening from one of said trunnions, an inlet valve and casing and an exhaust valve and casing on each side of said trunnion and between it and the end of said cylinder, pipes connecting said discharge-trunnion with each exhaust-casing, each of said exhaust-casings with an inlet-casing, and each inlet-valve casing with the interior of the cylinder, and two valve-operating levers supported in fixed bearings at their outer ends, and each extending inward beneath an inlet and an exhaust valve in positions to act upon the lower ends of the stems of said valves projecting through their casings, and pivoted at points central between said outlet and exhaust casings to bars connecting said casings, substantially as described.

In testimony whereof I have signed my name to this specification, in the presence of two subscribing witnesses, on this 17th day of January, A. D. 1890.

RICHARD J. ROGERS.
